United States Patent Office.

JOHN GULICK BAKER, OF PHILADELPHIA, PENNSYLVANIA.

Design No. 4,141, dated June 7, 1870.

DESIGN FOR A GRINDING-MILL STAND OR FRAME.

The Schedule referred to in these Letters Patent and making part of the same.

I, JOHN GULICK BAKER, of Philadelphia, county of Philadelphia, State of Pennsylvania, have invented or produced a Design for the Stand or Frame of a Grinding-Mill, of which the following is a specification.

The figure in the accompanying drawing represents an outline elevation of the stand or frame of a grinding-mill, made according to my design, A being a pillar or column, either fluted or plain, B the extended base of the column, and *a* the cap of the same, from which spring the two curved arms *c c*, the latter supporting the cylindrical and conical portions E and F of the frame, and the whole being surmounted by a hopper, H, the sides *b* of which may be either curved or straight.

J is a shelf or bracket adapted to one side of the column A.

The dotted lines *x* represent a spout, and the dotted lines *y* a horizontal bearing for the driving-shaft

of the mill; but these parts do not form an essential part of the design.

The beads *e e e*, &c., may be dispensed with, or other ornamentation substituted for the same.

Claims.

1. The design for the stand or frame of a grinding-mill, substantially as described, and as represented in and by the accompanying drawing.

2. The combination with the said stand or frame of the shelf or bracket J.

In testimony whereof I have signed my name to this specification in the presence of two subscribing witnesses.

JOHN GULICK BAKER.
